UNITED STATES PATENT OFFICE

2,463,777

SLEEVE PRESS

Benjamin S. Kagan, Moline, Ill., assignor to American Machine and Metals, Inc., East Moline, Ill., a corporation of Delaware

Application May 7, 1945, Serial No. 592,306

14 Claims. (Cl. 223—57)

1

The present invention relates generally to garment presses and more particularly to presses for sleeves and other tubular portions of garments, and has for its principal object the provision of a novel and improved pressing machine for pressing or ironing at least one half the circumference of a sleeve or the like in one operation or lay, without folding or creasing the sleeve.

It is known to those skilled in the art that it is not sufficient to place the sleeve over a form and merely apply a unidirectional pressure upon the pressing element, for the sides of the tubular garment are not in this manner subjected to pressures equal to that along the center of the garment portion. It is, therefore, a further object of my invention to provide a press in which the entire half circumference or more of the garment receives ample pressure to produce the desired results.

Sleeve presses are known to those skilled in the art, which will perform this function to a certain degree, and comprise complementary buck and head members having an inverted V-shaped cross section, one of the members being constructed with hinged sides to permit lateral pressure to be applied, either by expanding the buck or by contracting the head. However, this arrangement is subject to the inherent disadvantage that when pressure is applied the angle between the hinged sides changes, resulting in an unequal distribution of lateral pressure over the vertical dimension of the press elements. Accordingly, another object of my invention relates to the provision of means for producing a substantially equalized pressure over the sides of the press members.

In the accomplishment of this object, I do not hinge the sides of my buck member, but rather, provide bodily shiftable side plates, which are capable of a limited amount of free angular tilting movement and by exerting pressure against each plate at a point intermediate the top and bottom edges the plate can shift angularly as it moves outwardly, thereby conforming to the inner surface of the concave head member and substantially equalizing the pressure.

A further object has to do with the provision of an expandable buck which is appreciably simpler than those heretofore known in the art, with corresponding reductions in weight and cost of manufacture, and which is more efficient in operation.

These and other objects and advantages of my invention will be apparent to those skilled in the art after a consideration of the following

2

description, in which reference is had to the drawings appended hereto, in which

Figure 1 is a side elevational view of a sleeve press embodying the principles of my invention, showing the machine in pressing position, partly in section;

Figure 2 is a front elevational view of the pressing elements drawn to an enlarged scale and including diagrammatically a portion of the compressed-air-actuating circuit;

Figure 3 is a sectional elevational view, taken along a line 3—3 in Figure 2; and

Figure 4 is a sectional elevational view of the buck showing the pressing plates expanded to pressing position.

Referring now to the drawings, the sleeve press is indicated in its entirety by reference numeral 5 and comprises a main frame or housing 6 formed of vertically disposed side plates 7 and a horizontal plate or table 8. A yoke 9 is pivotally supported on a raised portion 10 of the housing 6, by means of a pivot pin 11 and has a forwardly extending head supporting arm 12 overhanging the table 8 and a downwardly extending actuating arm 13 on the opposite side of the pivot 11. The arm 12 carries a head 14 on a series of knife edges with spring restraint, indicated generally at 15, but inasmuch as this mechanism is known to those skilled in the art, no detailed description is deemed necessary.

The head 14 coacts with a buck 16 and is forced from a raised position above the buck to a pressing position in contact with the latter by means of a power device in the form of a cylinder 17, within which is slidably disposed a piston 18 mounted on a piston rod 19, projecting from one end of the cylinder 17. The cylinder is pivotally mounted within the housing 6 on a pivot pin 20, while the piston rod 19 is pivoted 40 at 21 to one end of a lever 22. The lever 22 is pivotally mounted by means of a pivot pin 23 on the frame or housing 6 within the walls 7. The opposite end of the lever 22 carries a camming roller 25, which is disposed within a slot 26 in a camming member 27, one end of the latter being pivoted at 28 on the yoke 9. The other end of the camming member 27 is adjustably secured to the yoke 9 by an adjusting screw 29 threaded through a boss 30 in the yoke 9 and 50 rotatably attached to the camming member 27. A hand wheel 31 facilitates adjustment of the screw for angularly adjusting the camming member about the pivot 28.

The yoke 9 is shown in a lowered position but without full pressure being applied. When the

piston 18 is moved to the upper end of the cylinder 17, the lever 22 is swung in a counter-clockwise direction, shifting the roller 25 downwardly in the slot 26 and forcing the yoke 9 clockwise about its pivot 11, thereby applying pressure upon the head 14.

A pair of counterbalancing springs 32 is connected to a bracket 33 pivoted at 34 on the yoke 9 and anchored at its lower end (not shown) to the frame 6. The springs 32 urge the yoke 10 in a counterclockwise direction to raise the head 14. The head is raised by the springs 32 when pressure is released from the cylinder 17, causing the roller to travel upwardly in the slot 26. The slot is curved in such a manner that the head moves downward rapidly until it approaches the buck 16, after which the movement is retarded, providing for exerting high pressure with correspondingly low speed of travel.

The press described herein above is disclosed in greater detail and claimed in Pat. 2,307,686, granted Jan. 5, 1943 to Koepcke, to which reference may be had if desired.

Coming now to that part of the structure with which my invention is more directly concerned, the buck 16 is mounted on a pedestal 40, which is supported on the table 8. The buck is supported in cantilever fashion from the standard 40 and comprises a longitudinally extending top rail 41 extending along the top of an inverted V-shaped support 42. The support 42 comprises a housing having a bottom member 43, a pair of upwardly converging, longitudinally tapered side walls 44, and a top member 45, on which the rail 41 is mounted. A pair of pressing plates 46 lie against the sloping side walls 44 and are supported thereon by dowel pins 47 rigidly fixed to the pressing plates and adapted to be inserted into holes 48 in the side walls 44, in which the pins fit loosely, providing for free bodily shifting movement of the plates 46 toward and away from the side walls 44 and also a limited amount of angular movement relative thereto for purposes to be explained.

Thus, the top rail 41 and the plates 46 define an inverted V-shaped surface on the buck, which is covered by a pressing pad 49, the outer convex surface 50 of which constitutes the pressing surfaces of the buck 16.

Means are provided for heating the buck. The walls 44 together with the top member 45, the bottom plate 43 and the web plates 67 and 68 form a steam chamber that heats the buck. Steam may be supplied to this heating space through a steam connection 60 and the condensation may be drained off through a pipe 61. By placing the heating chamber in the center of the buck the camming devices 71 are located outside of the heating chamber while the heat is still carried through the buck and plates to the extreme ends of the buck.

The head 14 is provided with a complementary concave pressing surface 51 formed by an inverted V-shaped metal plate 52, which receives the convex pressing surface 50. A steam jacket 53 embraces the plate 52 for heating the latter and comprises sloping side walls 54, bottom walls 55 interconnecting the lower edges of the plate 52 with the lower edges of the walls 54, a horizontal top wall 56 interconnecting the upper edges of the walls 54, and a pair of end walls 57, 58. Steam can be circulated through the jacket 53 by any conventional means (not shown).

It is obvious that if pressure is exerted only through the yoke arm 12, there is a concentrated

pressure between the apex of the pressure plate 52 and the top rail 41, with comparatively little pressure applied through the sides of the V-shaped surface 51. However, according to the principles of the present invention, side pressures are transmitted through the pressing plates 46, which are forced outwardly from the side walls 44 by means which will now be described.

A shaft 65 extends longitudinally through the buck between the side plates 44 and is journaled rigidly between a pair of web plates or intermediate transverse walls 67, 68, which are rigidly fixed, as by welding, to the side walls 44 of the support 42. The shaft 65 extends out of the latter through a journal bearing 69 and carries, at its outer end, a crank arm 70, rigidly fixed thereto. A pair of spaced camming devices 71 are fixedly mounted on the shaft 65, each device comprising a pair of longitudinally spaced arms 72 fixed on the shaft and extending radially outwardly therefrom in opposite directions, and a pair of cam rollers 73 on trunnions 74 journaled between the arms 72 on opposite sides of the shaft 65. The rollers 73 are adapted to bear upon wear plates 75, welded to the insides of the plates 46 and disposed within suitable openings in the side walls 44. Thus, it is evident that by turning the shaft 65 in a clockwise direction, as viewed in Figure 3, the rollers 73 are swung outwardly against the wear plates 75, forcing the plates 46 outwardly away from the side walls 44 and thus exerting a pressure through the pad 49 upon the sides of the pressing surface 51 in the head 14. The camming rollers are shown in solid lines in Figure 3 in relaxed position, and the dotted lines show the position of the arms 72 and rollers 73 in pressing position.

It will be noted that each pressing plate 46 receives pressure from two rollers disposed at longitudinally opposite ends of the plate and at points intermediate the top and bottom edges of the plates. This permits the plates 46 to move angularly relative to the side walls 44 as the plates 46 move bodily outwardly therefrom, causing the pressure exerted through the rollers to be distributed over the entire faces of the plates 46.

The shaft 65 is rocked by means of a control cylinder 80, within which is slidably disposed a piston 81 on a piston rod 82 pivotally connected at 83 to the arm 70 on the shaft 65. The cylinder 80 is pivotally connected by a pin 84 to the frame 6. The cylinder 80 is connected in communication with the yoke actuating cylinder 17 by a duct 85, 55 which connects to the side of the cylinder 17 at a point intermediate the ends of the latter but near the upper end thereof.

Fluid is supplied to the lower end of the yoke cylinder 17 through a supply duct 86. Preferably, compressed air is supplied from a suitable reservoir under control of valve mechanism, details of which do not constitute an important part of this invention, and therefore, since they are known to those skilled in the art, will be omitted in the interest of simplicity and clarity. The cylinder 80 is cut off from the supply duct 86 by the piston 81 until the latter passes the duct connection 85 near the upper end of its stroke, therefore the cylinder 80 begins to actuate the arm 70 just at the time the head 14 is beginning to exert pressure against the top rail 41. Thus, the pressure builds up substantially uniformly over the pressing surface 51, preventing the garment from being wrinkled or damaged.

The buck 16 extends beyond the end of the head

to receive a cuff clamp 93, which is mounted on an arm 94 pivotally mounted on the pivot pin 11 and independently swingable vertically into engagement with the buck extension under manual control of the operator, in a well known manner.

A rod 95 is loosely pivoted beneath the outer end of the buck 16 and extends inwardly toward the support 49 and is vertically swingable from its pivotal support, for the purpose of taking up slack in the sleeve during a pressing operation.

With the head 14 and cuff clamp 93 in raised position, a sleeve or other tubular garment is drawn over the padded buck and over the pivoted rod 95 with the body of the garment gathered over the pedestal. The cuff clamp 93 is clamped against the cuff of the sleeve after which the sleeve can be stretched smoothly over the buck. The weight of the rod 95 aids in smoothing the sleeve down on the sides of the buck. The head is then lowered by admitting air to the cylinder 17 through the supply pipe 86, forcing the piston 18 and piston rod 19 upwardly, which swings the yoke downwardly about the pin 11.

When the piston 18 uncovers the connection with the tube 85, the air flows through the tube 85, forcing the piston 81 upwardly in the cylinder 80, thereby rocking the shaft 65 and camming arms 72 to force the pressing plates 46 outwardly against the sides of the head 14. The operator then releases the air from the cylinders whereupon the springs 32 raise the head. At least half of the circumference of the sleeve has now been pressed. The sleeve is then turned to position the unpressed portion over the pressing surface 59 and the pressing operation is repeated, completing the pressing of the sleeve.

I claim:

1. In a garment press, a pair of complementary, relatively movable buck and head members, one of said members having a generally concave pressing surface and the other having a generally convex pressing surface, the latter member including a central body portion and at least one side portion shiftable relative to said body portion toward and away from said concave surface, a shaft rotatably mounted within said convex member, and a cam fixed to said shaft and engageable with said shiftable side portion to shift the latter, responsive to rotation of said shaft, in a direction toward said concave member for applying pressure thereto.

2. In a garment press, a pair of complementary, relatively movable buck and head members, one of said members having a generally concave pressing surface and the other having a generally convex pressing surface, the latter member including a support and a pair of side portions on opposite sides of said support and shiftable relative thereto toward and away from said concave surface, a shaft rotatably mounted within said convex member and extending longitudinally therein, and a pair of radially projecting arms mounted on said shaft and operatively engaged with said shiftable side portions, respectively, and responsive to rotary movement of said shaft to shift said opposite side portions toward said concave pressing surface for applying pressure thereto.

3. In a garment press, a buck having a generally inverted V-shaped cross section, a head movable relative thereto and having a complementary concave pressing surface, said buck including a pair of side plates serving as pressing surfaces and shiftable toward and away from said concave surface of said head, an actuating shaft rotatably mounted within said buck, and arm means fixed

on said shaft and rotatable therewith in engagement with said side plates to force the latter outwardly to apply pressure against the sides of said concave head surface.

5. In a garment press, a pair of complementary, relatively movable buck and head members, one of said members having a generally concave pressing surface and the other having a generally convex pressing surface, the latter member including a central body portion and at least one side portion shiftable relative to said body portion to bear uniformly against a part of said concave surface, a shaft rotatably mounted within said convex member, and a cam fixed to said shaft and engageable with said shiftable side portion to shift the latter, responsive to rotation of said shaft, in a direction toward said concave member for applying pressure uniformly over said side portion.

20. In a garment press, a pair of complementary, relatively movable buck and head members, one of said members having a generally concave pressing surface and the other having a generally convex pressing surface, the latter member including a support and a pair of side portions on opposite sides of said support and shiftable relative thereto to bear uniformly against parts of said concave surface, a shaft rotatably mounted within said convex member and extending longitudinally therein, and a pair of radially projecting arms mounted on said shaft and operatively engaged with said shiftable side portions, respectively, and responsive to rotary movement of said shaft to shift said opposite side portions toward said concave pressing surface for applying pressure uniformly over said side portions.

25. In a garment press, a buck having a generally inverted V-shaped cross section, a head movable relative thereto and having a complementary concave pressing surface, said buck including a pair of side plates serving as pressing surfaces and shiftable to bear uniformly against parts of said concave surface of said head, an actuating shaft rotatably mounted within said buck, and a cam means fixed on said shaft and rotatable therewith in engagement with said side plates to force the latter outwardly to apply pressure uniformly over portion of the sides of said concave head surface.

30. 7. For use in a garment press, a buck having a generally inverted V-shaped cross section and comprising a stationary supporting portion and a pair of side members shiftably mounted on opposite sides thereof, means adapted to move said side members outwardly from and inwardly toward said supporting portion, a shaft rotatably mounted in said supporting portion between said side members and having arms extending oppositely to engage the side members, and means for rotating said shaft to cause said arms to force said side members outwardly.

35. 8. For use in a garment press, a buck having a generally inverted V-shaped cross section and comprising a stationary supporting portion and a pair of side members shiftably mounted on opposite sides thereof, means adapted to move said side members outwardly from, and inwardly toward said supporting portion, a shaft extending longitudinally within said supporting portion and rotatably mounted thereon, and a pair of radially extending cams fixed to said shaft at each end of said buck, each pair of cams projecting oppositely to engage said side members, respectively, and adapted to force the side mem-

bers outwardly from said supporting member responsive to rotation of said shaft.

9. An expanding sleeve buck comprising a stationary supporting portion having a longitudinally extending direct pressure rail along the top thereof and a pair of downwardly and outwardly sloping sides on opposite sides thereof, respectively, pressing plates shiftably mounted on said sloping sides, means providing for movement of said plates outwardly from, and inwardly toward, said sloping sides, a longitudinally extending shaft within said buck, and at least one pair of radially extending arms rigid on said shaft and connected with said plates, respectively, and operative to force the plates outwardly from said sloping sides responsive to rotation of said shaft.

10. An expanding sleeve buck comprising a stationary supporting portion having a longitudinally extending direct pressure rail along the top thereof and a pair of downwardly and outwardly sloping sides on opposite sides thereof, respectively, pressing plates shiftably mounted on said sloping sides, means providing for movement of said plates outwardly from, and inwardly toward, said sloping sides, a longitudinally extending shaft within said buck, and at least one pair of opposed camming arms fixed to said shaft and extending outwardly into engagement with said pressing plates, for forcing the plates away from said sloping walls to expand the buck, said arms having rollers journaled thereon in rolling engagement with said plates, respectively.

11. An expanding sleeve buck comprising a stationary supporting portion having a longitudinally extending direct pressure rail along the top thereof and a pair of downwardly and outwardly sloping sides on opposite sides thereof, respectively, pressing plates shiftably mounted on said sloping sides, means providing for movement of said plates bodily outwardly from, and inwardly toward, said sloping sides and for a limited amount of free angular movement relative thereto, and actuating mechanism disposed within said buck adapted to apply outward pressure against said plates intermediate the top and bottom edges thereof, causing said plates to shift angularly coincident with outward expanding movement thereof, thereby substantially equalizing the pressure between the top and bottom edges against a complementary cooperative pressing element.

12. An expanding sleeve buck comprising a stationary supporting portion having a longitudinally extending direct pressure rail along the top thereof and a pair of downwardly and outwardly sloping sides on opposite sides thereof,

respectively, pressing plates shiftably mounted on said sloping sides, means providing for movement of said plates bodily outwardly from, and inwardly toward, said sloping sides and for a limited amount of free angular movement relative thereto, a rotatable shaft extending longitudinally within said supporting portion and having radially extending cams engaging said plates intermediate the top and bottom edges thereof, and means for turning said shaft about its major axis to apply outward pressure against said plates, causing the plates to shift angularly coincident with outward expanding movement thereof, thereby substantially equalizing the pressure between the top and bottom edges against a complementary cooperative pressing element.

13. For use in a garment press, a buck having a generally inverted V-shaped cross section and comprising a stationary supporting portion and a pair of side members shiftably mounted on opposite sides thereof, respectively, means providing for movement of said side members outwardly from, and inwardly toward, said supporting portion, and for a limited amount of free angular tilting movement relative thereto about axes extending along either the top or bottom edges of said side members, a head movable relative to said buck and having a complementary concave pressing surface, and actuating mechanism disposed within said buck adapted to apply outward pressure against said side members intermediate the top and bottom edges thereof to cause said side members to shift angularly coincident with outward movement thereof into substantially equalized pressure relation with said concave pressing surface in said head.

14. The combination set forth in claim 13, including the further provision that said mounting means comprises a plurality of dowel pins attached to the inner surface of said side members adapted to fit loosely within registering apertures in said stationary supporting portion.
